UNITED STATES PATENT OFFICE.

JAMES BROCKIE, OF FOREST HILL, LONDON, ENGLAND.

MAGAZINE ARC-LAMP.

1,229,876.

Specification of Letters Patent. Patented June 12, 1917.

Application filed February 16, 1914. Serial No. 819,015.

To all whom it may concern:

Be it known that I, JAMES BROCKIE, a subject of the King of Great Britain, residing in London, England, and whose post-office address is 41 London road, Forest Hill, in the county of London, England, have invented certain new and useful Improvements in Magazine Arc-Lamps, of which the following is a specification.

10 This invention relates to magazine arc lamps and has for its main object to substantially annul the period of darkness in changing from one pair of carbons to another.

15 According to the present invention the arc is re-started when the new carbons have been fed forward to within a distance less than that between the burning carbons, the extinction of the lamp being momentarily effected either by temporarily short circuiting it or by blowing out the existing arc by any suitable means.

Two main advantages of this invention are (1) that a main coil can be used to separate the magazines in order to obtain or strike the arc and to retain the magazines in that position, the further or future actual feed of the carbons being effected or controlled by the shunt coil only, instead of 25 by the usual differential arrangement of coils; and (2) the arc when first formed or struck occupies the same position in relation to the lamp reflector as the old or consumed carbons, thus securing greater steadiness of the light during the first few minutes after a new pair of carbons has commenced to burn. The invention further consists in a certain novel arrangement, construction and combination of parts hereinafter more fully described and finally 35 pointed out in the appended claims.

In the accompanying drawings Figure 1 is a side elevation showing the essential parts of a double chamber magazine arc lamp embodying this arrangement, Fig. 2 being an end elevation on an enlarged scale of one of the double magazines and carbon feeding device. Fig. 3 is a diagrammatic view showing the electrical circuits for the 45 different operative parts of the lamp. It will be understood, however, that the invention is of general application and may be applied to single chamber magazine lamps, as well as to double chamber magazine lamps.

The present invention is applicable generally to arc lamps, and carbon storing magazines of different types may be used. As an example, the carbon storing magazines shown in the present instance are of 60 the type disclosed generally in my British Patent, No. 27,725 of 1906. These magazines in the present instance comprise a pair of double-walled receptacles 1 and 1'. Each magazine is divided centrally to provide a 65 pair of carbon storing chambers 13, these chambers being supplied with carbons from their respective outer sides, and the springs 14 shown in Fig. 2 operate on the carbons and between the walls of the respective 70 magazines to feed the carbons from the outer sides toward the center of the magazine. The center of the magazine is slotted vertically or longitudinally, and an endless chain 15 operates in the slot. One of these 75 chains is provided for each magazine, the chains passing over suitable sprocket wheels 16 and 17 toward the upper and lower ends of the respective magazines, and the inner stretches of the chains are caused to move 80 downwardly or toward the arcing point by an electric motor 19, the shaft 20 of which is shown geared to the sprocket wheels 16 of the two chains. Each chain carries a 85 suitable number of projections 3, these projections being spaced at suitable intervals along the chain, depending upon the length of the carbons, and these projections extend alternately from opposite sides of the chain. In consequence, the downward movement 90 of the inner stretch of the chain of each magazine will cause the projection 3 extending to one side of the chain to feed a carbon from that side of the magazine, while the next projection 3 on the chain which extends to the opposite side thereof will subsequently feed a carbon from the opposite side of the magazine, this alternate feeding of the carbons being repeated during the 95 automatic operation of the lamp.

One of the magazines, the magazine 1' in the present instance, is fitted with a pair of contacts 2 which are insulated therefrom, and these contacts are adapted to be engaged alternately and successively by the carbon 105 feeding projections 3 on the respective chains to perform functions to be hereinafter described.

The magazines are attached at their upper ends to the under side of a crown plate 11. 110

In order to enable the carbons to be brought together to close the circuit between them and to subsequently separate to draw the arc, the magazines are relatively movable at their lower ends. As shown, the magazines are supported from the crown plate 11 by the brackets 12, and one of the magazines, the magazine 1 in the present instance, is pivoted or hinged on the axis 18 whereby the lower end of this magazine may swing toward and from the lower end of the coöperating magazine. The movement of the magazine 1 toward and from the coöperating magazine is effected by a series-connected solenoid 6, the vertically movable core 7 of which is connected by linkage 8 to the magazine 1 whereby energization of the solenoid 6 will operate the linkage 8 to relatively separate the lower ends of the magazines while deënergization of this solenoid will cause the lower end of the magazine 1 to move toward the lower end of the coöperating magazine. Feeding of the carbons by the motor 19 is controlled by the shunt solenoid 4, the vertically movable core of this solenoid being operatively connected to an intermediately pivoted lever 9, and this lever in turn controls contacts 23 which are included in the circuit of the feed motor 19. The lever 9 also controls the contacts 22 of a cut-out 5, the latter performing the function of extinguishing the arc between the burning carbons preparatory to their replacement by a fresh pair of carbons. The contacts 22 and 23 controlled by the shunt solenoid 4 are so positioned that the normal energization of the shunt solenoid 4 during the operation of the lamp will be sufficient to engage the contacts 23 and cause the motor 19 to operate to feed the carbons, but such normal energization will be insufficient to move the lever 9 to the point where the contacts 22 of the cut-out 5 will be engaged. However, when the shunt solenoid receives an energizing current of increased strength, the lever 9 will be moved sufficiently to engage the contacts 22.

According to the present invention, when a pair of carbons has been consumed to an extent which makes their replacement desirable or necessary, a fresh pair of carbons has been fed forward until their operative ends are closer to one another than are the ends of the burning carbons, the arc between the burning carbons is then extinguished, the magazines are caused to move relatively toward one another to bring the ends of the fresh carbons into engagement to close the circuit between them, and the magazines are then relatively separated to draw the arc between the fresh carbons. This cycle of operations is repeated automatically when it becomes necessary to replace the consumed carbons. Fig. 3 shows diagrammatically the circuits connecting

the different parts of the lamp as heretofore described whereby this cycle of operations will occur automatically. In this figure, C, C represent the pair of burning carbons and C', C' represent a fresh pair of carbons, the same being fed forward sufficiently to bring their operative ends closer to one another than the operative ends of the burning carbons C, C. In the diagram, 30 represents one side of the line circuit, it 70 being connected to one of the carbons C, and 31 represents the circuit of the solenoid 6 which is connected in series between the carbons and the other side 32 of the line. The contacts 22 of the cut-out 5 are connected, respectively, to the two sides 30 and 32 of the line circuit by the circuits 33 and 34. The contacts 23 which control the carbon feeding motor 19 are connected in series in the motor circuit 35. The solenoid 4 is 75 connected in shunt with the carbons by the circuit 36 one side of which is connected to one carbon and the other side of which is connected to the other carbon and contains a resistance R. The contacts 2 are insulated 80 from the magazine supporting them and are connected in the circuit of the solenoid 4 by a conductor 37 which shunts out the resistance R of that circuit. In the diagram, the parts are shown in the positions 85 they occupy immediately prior to the replacing of the consumed carbons C, C by the fresh carbons C', C'. The arc at this time is passing between the consumed carbons C, C, although the points or operative 90 ends of the fresh carbons are in closer proximity to one another. The contacts 2 are 95 so located that one of these contacts will be engaged by one of the projections 3 on the adjacent chain when the carbons have been 100 consumed to the extent which renders their replacement desirable or necessary. When one of the projections 3 engages one of the contacts 2, a current of maximum strength 105 passes from the side 30 of the line circuit through the conductor 37 which shunts out the resistance R and thereby energizes the shunt solenoid 4 to its full strength. This 110 causes the lever 9 to rock to its maximum extent, engaging the contacts 22 of the cut-out 5, and the cut-out thereby operates to short-circuit the carbons and the series solenoid 6. This short-circuiting of the carbons 115 and the series solenoid extinguishes the arc between the burning carbons and simultaneously deënergizes the series solenoid. This deënergization of the series solenoid causes the lower ends of the magazines to 120 come together, thereby engaging the operative ends of the fresh pair of carbons 125 (which are further advanced than the old or burned carbons), thus reëstablishing the circuit through the fresh carbons and the series solenoid, and consequent energization 130 of the series solenoid causes separation of

the fresh carbons which draws the arc between them. The movement of the lever 9 to close the cut-out which short-circuits the carbons and series solenoid also engages the contacts 23 in the circuit of the carbon feeding motor. This causes the carbon feeding motor to operate to feed the fresh carbons C', C' to the point where their operative ends are in closer relation than the operative ends of the burning carbons, and it also carries the operative projection 3 off the contact 2, thereby enabling the lamp to resume its normal operation. In the normal operation of the lamp, the resistance R is included in the circuit of the shunt solenoid 4 so that this solenoid has a strength only sufficient to control the contacts 23 which govern the operation of the carbon feeding motor 19, and the current passing in series through the solenoid 6 causes this solenoid to govern the arc gap between the carbons.

I claim as my invention:

1. A magazine arc lamp comprising, in combination, means for feeding carbons in pairs toward one another, said means being operative to feed a new pair of carbons to supplant the burning carbons and to a distance less than that between the points of the burning carbons, means controlled by the carbon-feeding means and embodying a cut-out for short-circuiting the carbons to extinguish the arc between the burning carbons, and an electro-magnetic device connected in series with the carbons and operative to cause the points of the new carbons to move into and out of engagement when such device is deenergized and energized, respectively.

2. An arc lamp comprising, in combination, means for feeding carbons in pairs toward one another, electro-magnetic means connected in series with the carbons for causing the points of the carbons to move into and out of engagement, and means including a short-circuiting cut-out for the carbons, controlled by the carbon-feeding means, for extinguishing the arc between one pair of carbons and for deenergizing and energizing said electro-magnetic means to strike an arc between another pair of carbons.

3. An arc lamp comprising, in combination, means for feeding carbons toward one another in pairs, said means being operative to feed a fresh pair of carbons to supplant a pair of burning carbons and to a distance less than that between the points of the burning carbons, an electro-magnetic device connected in series with the carbons and operative to move the points of the new carbons into and out of engagement, and means controlled by the carbon-feeding means for short-circuiting the burning carbons to extinguish the arc between them and for de-

energizing and energizing said series electro-magnetic device to strike an arc between the fresh pair of carbons.

4. In a magazine arc lamp, the combination of means for feeding carbons toward one another in pairs, said means being operative to feed a new pair of carbons to supplant a pair of burning carbons when the latter have been fed to a predetermined point, an electro-magnetic device connected in series with the carbons and operative to cause the points of the new carbons to move into and out of engagement when said electro-magnetic device is deenergized and energized, respectively, a second electro-magnetic device embodying a short-circuiting switch connected in shunt with the carbons to extinguish the arc between the burning carbons and to control the operation of said series electro-magnetic device, and means operative by the carbon-feeding means for controlling the circuit of said second electro-magnetic device to cause operation of the latter, when a new pair of carbons has been fed to a predetermined position, to extinguish the arc between the burning carbons and to deenergize the first-mentioned series electro-magnetic device to cause contact of the points of the new carbons.

5. An arc lamp comprising, in combination, means for feeding carbons in pairs toward one another, a cut-out for short-circuiting and thereby controlling the supply of current to said carbons, the carbon-feeding means being operative to feed a new pair of carbons to supplant the burning carbons at a predetermined point in the feed of the old carbons, an electro-magnetic device connected in series with the carbons and operative when deenergized to cause the points of the new carbons to come into contact and operative when energized to separate the new carbons, a second electro-magnetic device controlling the operation of the carbon-feeding means and the cut-out and operative when energized to interrupt the feed of the carbons to operate the cut-out to short-circuit the carbons, and to deenergize the first-mentioned series electro-magnetic device, means operative by the carbon-feeding means to establish, through said second-mentioned electro-magnetic device, a circuit in shunt with the carbons, whereby the cut-out is operated to extinguish the arc between the burning carbons when the new carbons have been fed to a predetermined position, and to deenergize the first-mentioned series electro-magnetic device to cause engagement of the new carbons to complete a circuit between them.

6. A magazine arc lamp comprising means for feeding carbons toward one another in pairs and adapted to feed a new pair of carbons to supplant burning carbons at a predetermined point in the feed of said

burning carbons, electro-magnetic means in series with the carbons and operative to cause the carbons to move into and out of engagement, an electro-magnetic device in shunt with the carbons and controlling the operation of the carbon-feeding means, said shunt electro-magnetic device embodying a cut-out for short-circuiting the carbons, whereby the arc between the burning carbons is momentarily extinguished and said series electro-magnetic means is deenergized to cause contact between the points of the

new carbons, and means operative by the carbon-feeding means for controlling the operation of said shunt electro-magnetic device.

In testimony whereof I have signed my name to this specification in the presence of two subscribing witnesses.

JAMES BROCKIE.
